UNITED STATES PATENT OFFICE.

JAMES B. WILLIAMS, OF OAKLAND, CALIFORNIA.

INSULATED ELECTRIC CONDUCTOR.

SPECIFICATION forming part of Letters Patent No. 451,587, dated May 5, 1891.

Application filed November 13, 1890. Serial No. 371,330. (No model.)

To all whom it may concern:

Be it known that I, JAMES B. WILLIAMS, a citizen of the United States, residing at Oakland, Alameda county, California, have invented certain new and useful Improvements in Insulated Electric Conductors; and I do declare the following to be a full, clear, and exact description of the invention, such as will enable others skilled in the art to which it appertains to make and use the same, reference being had to the accompanying drawings, and to the letters marked thereon, which form part of this specification.

My invention relates to insulated electric conductors; and its novelty consists in the means employed to keep the conductor substantially concentric with the dielectric employed to insulate it when the said dielectric is composed in whole or in part of vulcanized materials and is softened by the action of heat.

The insulated electric conductors referred to consist of a central metallic conductor, which may be solid, stranded, or tubular, and which is substantially circular in cross-section, surrounded by a dielectric which is itself usually surrounded by one or more water-proof protecting-coverings.

Dielectrics may be divided into two classes— those which are simple or formed of a homogeneous material and those which are compound or composed of layers of different materials—for instance, an inner layer of one kind of material and an outer of another kind. These may have an inner layer of unvulcanized material and an outer layer of vulcanized material, or they may both be of vulcanized material, in which case they should be of different kinds. An example of the former is a dielectric composed of an inner layer of a rubber composition containing no sulphur and an outer layer of one containing sulphur, and an example of the latter is a dielectric composed of an inner layer of a rubber composition containing sulphur and an outer layer of a gutta-percha composition containing sulphur. In all cases the outer layer of a compound dielectric should be relatively thin.

Under the usual conditions of use to which insulated electric conductors are subjected it will occur at times, either through outside influences or from the passage of currents of

unusual strength through the conductor, that the dielectrics will become heated and softened, and thus offer less resistance to the weight of the conductor, which gradually sinks down until it comes into sufficiently close contact with the exterior surface of the dielectric so as to destroy its value. This is especially apt to occur where conductors of great length are employed and which rest against hard substances, such as pipes in the ground and the like.

My invention has for its object the overcoming of this difficulty by keeping the conductor in position and substantially concentric with its dielectric under conditions when the material of the dielectric will itself become soft.

In an application for Letters Patent of the United States filed by me July 12, 1890, Serial No. 358,571, I have described and claimed as my invention in general terms a centering device composed of fibrous material saturated with an insulating material not so readily softened by heat as the material of the dielectric, and also the specific combination of such a centering device with the conductor provided with an unvulcanized dielectric.

The subject of the present application may be considered as an improvement upon or modification of the invention described in that application, and relates more particularly to the combination, with the conductor, of the centering device, hereinafter described, when the dielectric is in whole or in part composed of vulcanized material. Such dielectrics, while not so readily softened by heat as those composed of unvulcanized material, are subject to almost the same disadvantages in use.

While insulated electric conductors provided with vulcanized dielectrics have been in common use for many years, heretofore there has been no means known to me whereby the conductors could be kept in the center of their surrounding dielectrics when heated sufficiently to soften the latter, and the value of a centering device in this connection will be at once apparent to any one familiar with the conditions under which such insulated electric conductors are used.

I accomplish my purpose by placing around the conductor and embedded in the dielectric

a centering device composed of fibrous material saturated with a suitable insulating material, preferably by means of a volatile solvent not injuriously affected by sulphur during the process of vulcanization, and preferably not so readily softened by heat as the materials composing the dielectric employed in each case, and so arranged that it is in contact with the conductor at as few points as possible, still retaining its function of support. The simplest form of this centering device is a yarn or cord of fibrous material previously saturated with an insulating material not so readily softened by heat as the materials composing the dielectric, and also such as is not injuriously affected by sulphur during the process of vulcanization, such as cotton yarn saturated with shellac dissolved in alcohol. This device is in the majority of cases wound around the conductor and suitably secured thereto when necessary before the application of the dielectric. Then when the dielectric and its external water-proof covering have been applied and the conductor is heated from any cause sufficiently to soften the dielectric the material with which the centering device is saturated is not softened and the conductor is kept in place.

In the drawings, in which the same letters refer to the same parts in all of the figures, Figure 1 is a transverse section of an insulated electric conductor provided with my centering device in its simplest form and showing a simple dielectric completely surrounding the same. Fig. 2 is a similar view of the same with a protecting-covering placed between the dielectric and its external water-proof protecting-covering. Fig. 3 is a similar view showing a compound dielectric; and Fig. 4 is a central longitudinal section of the device shown in Fig. 1, the parts in all of the figures being shown in relative positions, but not necessarily in relative sizes.

In the drawings, W is the conductor surrounded by the dielectric I, composed of vulcanized materials and inclosed in a water-proof protecting-covering L, usually made of lead. S is a centering device, consisting of a cord or cords wound around the conductor in the manner shown.

P is a protecting-layer surrounding the dielectric and placed inside of the protecting-covering L after the dielectric and centering device have been placed in position and are ready for use, and is preferably made of fibrous material saturated with a suitable insulating material.

I' is a compound dielectric, consisting of an inner layer *i* of unvulcanized material and an outer layer *i'* of vulcanized material.

The manner of placing my centering device in position in its simplest form—that of a spiral—when the dielectric is compound and has an inner layer of unvulcanized material and an outer layer of vulcanized material is as follows: The fibrous material of which the cord is composed is thoroughly and completely

saturated with its insulating material, so that its interstices are filled with the solid particles of the same, and while this is in a plastic state the cord is applied to the conductor in a spiral form. The pitch of the spiral will depend in each instance upon the thickness and kind of material used as a dielectric, the size of the conductor, and the conditions under which the insulated conductor is to be used. For instance, if the insulated conductor is to be kept straight, or nearly so, and is to be used in comparatively cool situations, the pitch of the spiral should be steeper than when it is to be frequently bent or used in situations where it is liable to become heated. An intelligent and skilled workman can readily determine the pitch of the spiral in each instance, and no fixed rules therefor can be given. When the centering device has been so applied and suitably secured to the surface of the conductor by cement, if the insulating material with which it is saturated does not act in that capacity a layer of the unvulcanizable portion of the dielectric is placed by means of suitable apparatus upon the entire surface of the conductor which is to be insulated, so as to embed the centering device therein, and the vulcanizable layer, which should be relatively thin, is then placed in position around it in the manner well known to the art.

When the dielectric is simple, the most satisfactory way of applying the centering device, if in the form of a spiral, is in many cases to force it into the dielectric after the latter has been applied to the conductor and while it is in a plastic state and before its vulcanization. When it is to be thus applied, usually by means of rolls, great care should be taken to completely saturate the fibrous material with the insulating material employed, so that its interstices will be completely filled with the solid particles of the same.

After the centering device has been placed in position the dielectric is vulcanized under pressure in the usual manner. In the majority of cases it is advisable to protect the dielectric during vulcanization from the action of moisture by a sheath of tin, which is afterward removed. After vulcanization, if any spaces should be found to exist in the dielectric they should be filled with paraffine or some suitable material. The finished conductor is then provided with its external protecting water-proof covering or coverings, as may be deemed desirable.

It is evident that wide modifications in detail may be made in my invention, especially in the form and materials used for the centering device, without departing from its essential features. I may make this device in the form of an open braid, or almost any practical structure having raised portions, and I may use any of the well-known fibrous materials and insulating materials suitable for the accomplishment of my purpose; but,

however the device is formed or of whatever materials, its outer surfaces must be substantially equidistant from the axis of the conductor, and it must be of such a nature that the insulating material with which it is saturated will not be injuriously affected by sulphur during vulcanization, and which will preferably require a higher temperature to soften it than that required to soften the dielectric in which it is embedded.

What I claim as new is—

1. In an insulated electric conductor, the combination, with a central metallic conductor provided with a vulcanized dielectric, of a centering device also surrounding the conductor and embedded in the dielectric and composed of fibrous material saturated with an insulating material not injuriously affected by sulphur during the process of vulcanization.

2. In an insulated electric conductor, the combination, with a central metallic conductor provided with a compound dielectric wholly or partly composed of vulcanized materials, of a centering device also surrounding the conductor and embedded in the dielectric and consisting of fibrous material saturated with an insulating material not injuriously affected by sulphur during the process of vulcanization.

3. In an insulated electric conductor, the combination, with a central metallic conductor provided with a vulcanized dielectric, of a centering device also surrounding the conductor and embedded in the dielectric and consisting of fibrous material saturated with an insulating material not so readily softened by heat as the materials composing the dielectric.

4. The combination, with an electric conductor provided with a compound dielectric, the inner layer of which is composed of unvulcanized material and the outer layer of vulcanized material, of a centering device consisting of fibrous material, also surrounding the conductor and embedded in the dielectric and saturated with an insulating material not so readily softened by heat as the materials composing the dielectric.

5. The combination, with an electric conductor provided with a dielectric composed of vulcanized material and a centering device embedded within the same and consisting of fibrous material saturated with an insulating material not so readily softened by heat as the materials composing the dielectric, of a layer of fibrous material surrounding the dielectric and saturated with a suitable protecting insulating material, as shown.

6. The combination, with an electric conductor provided with a surrounding compound dielectric having an inner unvulcanized and an outer vulcanized layer and in which dielectric is embedded a centering device also surrounding the conductor and consisting of fibrous material saturated with an insulating material not so readily softened by heat as the materials composing the dielectric, of a layer of fibrous material surrounding the dielectric and saturated with a suitable protecting insulating material, as shown and described.

In testimony whereof I affix my signature in presence of two witnesses.

JAMES B. WILLIAMS.
